UNITED STATES PATENT OFFICE.

LOIS McG. WILLIAMS, OF FORT THOMAS, KENTUCKY, ASSIGNOR TO THE WADSWORTH WATCH CASE COMPANY, OF DAYTON, KENTUCKY, A CORPORATION OF KENTUCKY.

DESIGN FOR A COMBINATION WATCHCASE PENDANT, BOW, AND CROWN.

Application filed May 15, 1922. Serial No. 2,251. Term of patent 14 years.

To all whom it may concern:

Be it known that I, Lois McG. WILLIAMS, a citizen of the United States, residing at Fort Thomas, in the county of Campbell and State of Kentucky, have invented a new, original, and ornamental Design for Combination Watchcase Pendants, Bows, and Crowns, of which of the following is a specification, reference being had to the accompanying drawing, forming part hereof.

In the drawing:

Fig. 1 is a plan view of a combination watch-case pendant, bow and crown embodying my design, its relation to the other

watch-case parts being indicated by a conventional showing of the latter by dotted lines;

Fig. 2 is a front elevation thereof; and
Fig. 3 is a side elevation.

I claim:

The ornamental design for a combination watch-case pendant, bow and crown, substantially as shown.

LOIS McG. WILLIAMS.
